INVENTOR

Wm. R. Brown

BY *Wm. R. Brown*
ATTYS

UNITED STATES PATENT OFFICE.

WILLIAM ROBERTSON BROWN, OF OAKVILLE, MANITOBA, CANADA.

PORTABLE BUILDING.

Application filed October 4, 1920. Serial No. 414,633.

To all whom it may concern:

Be it known that I, WILLIAM ROBERTSON Brown, of the town of Oakville, in the Province of Manitoba, Canada, have invented 5 certain new and useful Improvements in Portable Buildings, of which the following is the specification.

The invention relates to improvements in portable buildings and particularly to a 10 building which can be utilized for housing and feeding cattle in the winter time and for storing grain in the fall or harvest time and the object of the invention is to provide a portable building having one side 15 wall thereof constructed so that it can be opened up and such that there will be uprights exposed forming a rack like side, such feature permitting of the use of the building for housing and feeding the cattle 20 in a special way as hereinafter described and also permitting, when the side is closed, of the storing of grain during harvest time.

With the above object in view the invention consists essentially in the arrangement and construction of parts hereinafter 25 more particularly described and later pointed out in the appended claim, reference being had to the accompanying drawing in which:—

30 Fig. 1 is a perspective view of a barn or building constructed in accordance with my invention.

Fig. 2 is a sectional view through the barn with the open side butted against a 35 stack on the field.

Fig. 3 is a plan view showing diagrammatically the manner in which the barn is pulled up to the stack.

In the drawing like characters of reference indicate corresponding parts in the 40 several figures.

1 represents the building or barn which is mounted on suitable skids 2 and 3, the skids being placed directly under the floor 45 4 and being located crosswise of the barn. One end of the barn is provided with the customary hinged entrance door 5 and the roof and other walls with the exception of one side wall are of ordinary construction. 50 The side wall last referred to is arranged so that it can be opened or closed as wished and presents the usual spaced uprights 6 extending between the sill 7 and the roof beam 8, 9 is a base board detachably secured by hooks 9' to the lower ends of the

uprights and partially closing in the side for a predetermined height.

10 is a gate having the upper edge pivotally secured as by hinges 11 to the roof beam 8 which supports it. This gate or 60 side door is of a size such that when down it will close the side of the barn, the lower edge thereof swinging in immediately above the upper edge of the foot board 9.

Whilst I have described it as a single 65 door it will be readily understood that it could be divided into several doors if wished, each one being independent of the other.

Means are provided for raising the side 70 door to open position as shown in Fig. 2, such being a line 12 secured to each end of the door and passing over a pulley 13 located at the peak of the barn and suitably fastened to any form of catch 14 located 75 at the end of the barn.

On each end of the barn and adjacent the side remote from the gate I locate a winding drum indicated generally by the reference numeral 15, the drum in each instance 80 being provided with a winding cable 16.

When one wished to use this granary as a storage tank on the field he closes down the gate 10 to close the otherwise open side 85 and then puts his grain in the building in the ordinary way.

However, when one wishes to use the barn for housing cattle or other animals he draws the barn up to the side of a stack indicated at 17, the gate side of the barn 90 abutting the stack.

In referring to Fig. 3 one will see how this is done. The cables 16 are pulled off the drums and the free ends thereof are anchored as by driving spikes 18 and 19 95 into the ground at opposite sides of the stack. The attendant then turns the drums by applying cranks to the squared upper ends 15' thereof and accordingly draws the barn bodily upwardly to the stack on 100 the skids, the final position of the barn in respect to the stack being shown best in Figure. 2.

In the latter figure it will be seen that the side of the stack actually closes the adjacent side of the barn, with the result that when one removes the board 9 and lifts up the gate and fastens it in the position shown in Fig. 2 the side of the barn is closed by the stack and the hay, straw or such mate- 110

rial can be actually eaten by the cattle within the barn directly from the stack, the uprights 6 at this time forming a rack.

The farmer can from time to time tighten 5 up the cables to draw the barn closely to the stack, this being done as the hay or straw is gradually eaten. By so doing there will be very little cold air get into the barn from the stack side and the feed is at all times 10 within convenient range of the animals.

By providing a barn of this kind I not only allow it to be used for a double purpose; that is for storing grain and housing cattle, as occasion may demand, but I also 15 avoid the laborious operation of having to carry the food to the animals and feed them as would otherwise occur.

What I claim as my invention is:—

A portable housing provided with an open 20 side and with a door giving access therein,

spaced bars extending across the open side and forming a rack adapted to be engaged against a hay stack when the housing is used as a cattle shelter, and means for closing the open side when the housing is 25 to be used as a storage barn, said closure means comprising a foot member detachably supported by the rack and extending across the bottom of the open side and a door hingedly connected at its upper 30 edge to the housing so that in lowered position the lower edge of the door engages the foot member, thus entirely closing said open side.

Signed at Winnipeg this 22nd day of 35 September, 1920.

WILLIAM ROBERTSON BROWN.

In the presence of—

GERALD S. ROXBURGH,
K. B. WAKEFIELD.
